MULTIRATE METER

Filed Nov. 13, 1929

UNITED STATES PATENT OFFICE

GEORG MOHR, OF NUERMBERG, GERMANY, ASSIGNOR TO WESTINGHOUSE ELECTRIC & MANUFACTURING COMPANY, A CORPORATION OF PENNSYLVANIA

MULTIRATE METER

Application filed November 13, 1929, Serial No. 406,873, and in Germany November 17, 1928.

My invention relates to multi-rate or plural-tariff meters and more particularly to controlling systems therefor.

My invention has for an object to provide a switching system for multi-rate meters, whereby the day control is changed or made non-effective during a portion of the week, for example, during the Sunday rest period.

In my invention, the week control operates switches that render the usual automatic day control non-effective and place a manual day control in proper circuit relation for control purposes.

My invention thus provides means whereby any one of a plurality of rates may be made operative during the Sunday rest period, according to the season or operating conditions. My invention also permits two or more rates to be made operative during the Sunday rest period but at different times than during working days.

The features of my invention which are believed to be novel and patentable will be pointed out in the claims appended hereto.

For a better understanding of my invention, reference is made, in the following description, to the accompanying drawings, in which,

Figure 1 is a diagrammatic view of my invention applied to a triple-tariff meter;

Figs. 2, 3 and 4 are similar views of modifications of my invention, and

Fig. 5 is a schematic perspective view of a multi-rate meter constructed in accordance with my invention.

Figs. 1 to 3, inclusive, and 5 show switch systems for triple-tariff meters provided with two magnet cores 4 and 5 provided respectively with operating coils 1 and 2, in which one tariff is imposed when the coil 1 is energized, the second tariff when the coil 2 is energized, and the third tariff when both coils 1 and 2 are deenergized.

Referring to Figs. 1 and 5, the operating coils 1 and 2 are in series circuit with tariff switches 21 and 22 that are, in turn, in series circuit with a locking switch 30. The tariff switches 21 and 22 are actuated by control members 110 and 111, and 112 and 113, respectively, on the day disc 101 in a certain

section, and the locking switch 30 is opened by a control member 107 on a week disc 106 during the Sunday rest period.

The week disc 106 also controls a bridging switch 34 that is in series circuit with a changeover device 35. The latter device has three contacts 31, 32 and 33, of which the contact 31 is connected to the coil 1 and the contact 32 to the coil 2, while the contact 33 is an idle contact.

By opening the locking device 30 during the Sunday rest period, the tariff switches 21 and 22 are made non-effective. The first, second or third tariff is made operative during the Sunday rest period by placing the changeover device 35 on one of the contacts 31, 32 and 33, and closing the bridging switch 34 during said period by means of the week disc 106. The device is connected to any desired electric power circuit by means of terminals 10 and 11.

Referring to Fig. 2, the changeover device 35 is omitted and separate bridging switches 41 and 42 are provided for each coil. During the Sunday rest period, when the locking switch 30 is opened, the bridging switches 41 and 42 are controlled by the week disc 106 quite independently of the parallel switches 21 and 22.

In another modification (Fig. 3), the operating coils 1 and 2 and the tariff switches 21 and 22 are in parallel circuit with a resistor 12 that is connected in series circuit with a resistor 13. The locking switch 30 bridges the resistor 12 during the Sunday rest period. The resistor 13 is bridged by one of the switches 41 and 42 during this period.

As shown in Fig. 4, the tariff switches 21, 22 and 23 are connected in parallel circuit with operating coils 1, 2 and 3, respectively. A resistor 13 is inserted between the terminal 10 and the relays. Locking switches 301, 302 and 303 are inserted in the respective parallel branches of the tariff switches. The locking switches are mechanically coupled together and are normally closed. The coils 1, 2 and 3 are made non-effective by being short circuited by the tariff switches 21, 22 and 23. Bridging switches 41, 42 and 43 are in parallel circuit with the series connected switches 21,

301; 22, 302; and 23, 303. In this case also, during the Sunday rest period, by opening the locking switches 301, 302 and 303, the tariff switches 21, 22 and 23 are made non-effective and are replaced by bridging switches 41, 42 and 43, which are respectively controlled by the week disc and may be controlled independently of the tariff switches 21, 22 and 23.

16 As shown in Fig. 5, in which the various parts are shown separately for clearness, a clock train, indicated by rectangle 100, drives the day disc 101 and, through adjustable fingers 102 and 103, the star wheel 104, in the notches of which the spring 105 engages. The clock train drives, with a ratio of 1:2, the week disc 106 and the control disc 107 for the bridging switch 34.

20 The tariff switches 21 and 22, formed as snap switches, are actuated by members 110 to 113 adjustably mounted on the day disc 101. The triple-tariff counter mechanism is diagrammatically indicated at 114, the operating coils 1 and 2 and the change-over device 35 corresponding to those parts of the other figures.

30 In accordance with the provisions of the patent statutes, I have described the principle of operation of my invention, together with the apparatus which I now consider to represent the best embodiment thereof; but I desire to have it understood that the apparatus shown and described is only illustrative and that the invention may be embodied in other means.

I claim as my invention:

1. In a multi-rate meter, the combination with a plurality of controls, and means for selectively operating said controls during a predetermined period of time, of means for rendering said means non-effective during a predetermined fractional portion of said period of time, and means for operating said controls separately while said first means is non-effective.

40 2. In a multi-rate meter, the combination with means for changing from one tariff to another, including a control circuit, a tariff change-over element comprising an electro-magnet having a core and an operating coil therefor in said circuit, a switch in series circuit with said coil and means for periodically operating said switch, of means for rendering said operating means non-effective during a portion of each period, including a locking switch in said circuit, means for periodically opening said locking switch and a parallel-current branch around said switches having a bridging switch in circuit therewith, said bridging switch being closed by said means while said locking switch is open.

50 3. In a multi-rate meter, the combination with means for changing from one tariff to another, including a control circuit, a plurality of electro-magnets, each comprising a

magnetizable core and an energizing coil, in said control circuit in parallel-circuit relation with each other and means for selectively operating said energizing coils over a predetermined period of time, of means for rendering said magnet-operating means non-effective during a portion of said period of time, including an auxiliary circuit, means for placing said circuit in circuit relation with said energizing coils and means for disconnecting said magnet-operating means.

4. In a multi-rate meter having a plurality of integrating mechanisms, a control circuit including change-over electro-magnets and switches for selectively connecting said integrating mechanisms to the meter and a clock for daily operating said switches, the combination with a locking switch in said control circuit, and a parallel current branch around said switches, including a bridging switch, of control means driven by said clock for opening said locking switch and closing said bridging switch during a portion of each week.

5. In a multi-rate meter having a plurality of integrating mechanisms, a control circuit including change-over magnets, comprising, severally, a core and an energizing coil, and switches for selectively connecting said integrating mechanisms to the meter and a clock for daily operating said switches, the combination with a locking switch in said control circuit, and a parallel-current branch around said switches, including a bridging switch and a change-over device for selecting said energizing coils, of control means driven by said clock for opening said locking switch and closing said bridging switch during a portion of each week.

In testimony whereof I affix my signature.

GEORG MOHR.
